UNITED STATES PATENT OFFICE

1,972,056

ADJUSTABLE LIGHTING FIXTURE

Dirk G. Saaf, Chicago, Ill., assignor to Goodrich Electric Company, Chicago, Ill., a corporation of Illinois

Application July 25, 1932, Serial No. 624,446

8 Claims. (Cl. 240—78)

This invention relates to a fixture embodying an adjustable lamp socket, it being an object of the invention to provide a new and improved fixture of this character embodying a socket which can be adjusted without removing the reflector or globe holder associated therewith.

Another object is to provide a fixture of simple construction embodying a socket which may be readily adjusted without the use of tools.

10 Another object is to provide an adjustable lighting fixture embodying new and improved means for locking a socket in various positions of adjustment.

Further objects will become readily apparent 15 from the following detailed description taken in connection with the accompanying drawing, in which:

Fig. 1 is a fragmentary view of a preferred form of the invention, certain parts including a 20 reflector associated therewith being illustrated in central section.

Fig. 2 is a section along the line 2—2 of Fig. 1.

Fig. 3 is an enlarged fragmentary section along the line 3—3 of Fig. 4.

25 Fig. 4 is a fragmentary section along the line 4—4 of Fig. 3.

Fig. 5 is a fragmentary section similar to Fig. 4 with the exception that the parts are in the positions assumed during the adjusting operation, 30 being a section along the line 5—5 of Fig. 6.

Fig. 6 is a fragmentary section along the line 6—6 of Fig. 5.

While there is illustrated in the drawing and will hereinafter be described in detail a preferred form of the invention, it is to be understood that I do not intend to limit the invention to the specific construction and arrangement shown, it being contemplated that various changes may be made by those skilled in the art without departing from the spirit and scope of the invention 40 as expressed in the appended claims.

As illustrated in the drawing, the invention is disclosed as comprising a socket 10 adjustably mounted on a pair of laterally spaced and parallel depending strap-like arms or supporting members 11 which are secured at their upper ends to an inverted U-shaped part 12 carried on the lower end of an attaching bushing or support 13. This bushing is threaded internally for attachment to a conduit 14 containing wires 15 for connection with socket contacts 16, and is threaded externally to receive a collar 17 between which and a flange 18 on the bushing the upper end or base 19 of a reflector 20 is clamped. Since

the invention may be used to advantage in connection with a reflector having a somewhat slender tubular neck within which the socket is positioned, such a reflector neck 21 is illustrated. Thus a lamp 22 carried by the socket 10 may be 60 adjusted vertically so as to change the position of the light source of the lamp with respect to the effective portion of the reflector.

It is an object of the invention to provide a construction wherein the socket may be adjusted 65 vertically in the neck of the reflector without removing the reflector and for this reason the supporting members 11 are preferably resilient in character and are secured to the inverted U-shaped member 12 so that as viewed in Fig. 1 70 they tend to spread outwardly as indicated by the arrows 25. The socket which may be of porcelain or other suitable material and provided with the usual screw terminal (not shown) for the lamp, is herein disclosed as embodying a pair of laterally extending ears or lugs 26 and a metal ring or plate 27 which is secured to the lugs by means of screw devices 28. The metal ring portion of the socket is provided with a pair of slots 30 through which the members 11 extend when contracted 75 as shown in Figs. 5 and 6, the socket in this way being slidably mounted upon the supporting members so that it may be moved vertically with respect to the reflector.

In order to hold the socket effectively in its 80 adjusted position and to lock it against accidental displacement or movement due to the weight of the parts or vibration, the metal ring 27 is preferably provided with recesses 31 adjacent to and communicating with the slots 30. These recesses 90 are arranged to receive reduced portions of the members 11 formed by providing pairs of notches 32 in said members spaced longitudinally thereof, as illustrated most clearly in Figs. 1, 4 and 5. The recesses 31 are herein provided with beveled 95 or cam shaped ends 33 (Fig. 6) which are arranged to cooperate with beveled or cam shaped surfaces 34 forming the side walls of the notches 32 on the members 11 to provide a wedging action of said members into the recesses due to the 100 spreading action of the members. By properly proportioning the recesses and slots the supporting members do not engage the side walls 35 of the recesses, as illustrated in Fig. 3, but cam against the inclined end walls 33, and correspondingly the ring 27 cams against the beveled portions 34 of the notches 32 on the members 11 as 105 illustrated in Fig. 4. A tightly gripping yet readily disengageable locking means is thus provided which merely requires the manual drawing to- 110

gether of the lower ends of the members 11 for the purpose of adjusting the socket vertically thereon.

In order to facilitate the adjustment of the 5 socket, means is preferably provided for guiding the socket with respect to the supporting members so that when said members are contracted into the slots 30, as shown in Figs. 5 and 6, there is no 10 tendency for the ring to catch in the notches 32. As 15 is readily evident by referring to Fig. 5, these guide members are effective to keep the members 11 in alignment with the slots 30 when the ring 27 passes a pair of notches 32 and thereby provides 20 for a smooth sliding movement of the socket on the supporting members when said members are contracted into the slots 30.

I claim as my invention:

1. A device of the character described comprising, in combination, a support, a pair of resilient 25 metallic strap-like members extending from said support in laterally spaced relation and having a plurality of sets of opposed notches in the opposite edges thereof, a lamp socket, a ring secured to said socket having slots therein arranged to receive the wide portions of said members, and recesses adjacent to and communicating with said slots arranged to receive only the narrower portions of said members formed by said notches, said recesses and notches having beveled walls 35 interengageable with a wedging action to lock the socket in its adjusted position, and means projecting from said ring adjacent the ends of said slots and engageable with the edges of said members to guide the ring relatively to said members 40 when the members are contracted into said slots and facilitate movement of the socket longitudinally of the members.

2. A device of the character described comprising, in combination, a support, a pair of resilient 45 flat metallic members extending from said support in laterally spaced relation and having a plurality of notches in the edges thereof, a lamp socket, and a ring secured to said socket having slots therein arranged to receive the wide portions 50 of said members and recesses adjacent to and communicating with said slots arranged to receive only the narrower portions of said members formed by said notches, said recesses and notches having beveled walls interengageable with a 55 wedging action to lock the socket in its adjusted position.

3. An adjustable lighting fixture comprising, in combination, an attaching device, a pair of resilient supporting members secured to said device and extending therefrom in laterally spaced substantially parallel relation and having pairs of notches in the opposite edges thereof, a lamp 60 socket having a portion formed with slots arranged to admit said members when the members are drawn slightly together from a normally expanded position, recesses in said socket adjacent said slots arranged to receive the narrower portions of said members formed by said notches, said recesses and notches having cam-surfaces interengageable to lock the socket in its adjusted position, and guide means on said socket adjacent the ends of said slots arranged to span said notches to facilitate movement of the socket longitudinally of the supporting members.

4. An adjustable lighting fixture comprising, in combination, a support, a pair of members secured to said support and extending therefrom in laterally spaced substantially parallel relation and having notches in the edges thereof, a lamp socket having a portion formed with slots arranged to admit said members when the members are drawn slightly together from a normally expanded position, recesses in said socket adjacent said slots arranged to receive the narrower portions of the members formed by said notches, said recesses and notches having cam surfaces interengageable to lock the socket in its adjusted position.

5. A device of the character described comprising, in combination, a support, a pair of members secured to said support and extending therefrom in laterally spaced relation and having pairs of notches in the opposite edges thereof, a lamp socket having a portion formed with slots arranged to admit said members when contracted from a normally expanded position, and recesses in said socket adjacent said slots arranged to receive the narrower portions of said members formed by said notches to lock the socket in various positions of adjustment longitudinally of the members.

6. An adjustable lighting fixture comprising, in combination, a lamp socket, a pair of laterally spaced parallel supporting members for said socket one of which has a series of notches in the edges thereof, means secured to the socket having slots therein through which said members slide and provided with a recess into which the reduced portions of one member formed by said notches interengage, and means on the socket spanning said notches when the parts are disengaged to facilitate adjustment of the socket longitudinally of said members.

7. A device of the character described comprising, in combination, a support constituting a first part, a lamp socket constituting a second part, a pair of resilient flat metallic members extending from one of said parts in laterally spaced parallel relation and each having a plurality of pairs of opposed notches in the edges thereof, the other part having a portion formed with slots arranged to admit said members when the members are displaced slightly from their normal positions and having recesses adjacent said slots arranged to receive the narrower portions of said members formed by said notches, said recesses and notches having bevelled edges interengageable with a wedging action to lock one part in its adjusted position relatively to the other.

8. A device of the character described comprising, in combination, a support constituting a first part, a lamp socket constituting a second part, a pair of resilient flat metallic members extending from one of said parts in laterally spaced parallel relation, one of said members having a plurality of pairs of opposed recesses in the edges thereof, the other part being adjustable along said members and having a portion formed with slots arranged to admit said members when the members are displaced slightly from their normal positions and having a recess adjacent one of said slots arranged to receive the narrower portions of the member formed by said pairs of recesses, certain of said recesses having bevelled edges engageable with a wedging action to lock one part in its adjusted position relatively to the other.

DIRK G. SAAF.
